UNITED STATES PATENT OFFICE

110,341

DESIGN FOR AN EDIBLE CONTAINER OR THE LIKE

William H. Carter and James R. Rudderforth,
Washington, D. C.

Application February 3, 1938, Serial No. 74,848

Term of patent 14 years

To all whom it may concern:

Be it known that we, William H. Carter and James R. Rudderforth, citizens of the United States, residing at Washington, District of Columbia, have invented a new, original, and ornamental Design for an Edible Container or the like, of which the following is a specification, reference being had to the accompanying drawing, forming part thereof.

Figure 1 is a top plan view of an edible container showing my new design;

Figure 2 is a view in side elevation of the article as illustrated in Figure 1;

Figure 3 is a sectional view taken substantially on the line 3—3 of Figure 1.

The dominant features of the design consist of the ribs, short rounded ends, and pocket arranged in an edible container of the configuration shown.

We claim:

The ornamental design for an edible container or the like, as shown and described.

WILLIAM H. CARTER.
JAMES R. RUDDERFORTH.
